EDGAR WOLTERS, OF HAMBURG, GERMANY

THERAPEUTICAL DEVICE

Application filed June 6, 1928. Serial No. 283,283.

This invention relates to that class of therapeutical devices which is used in treating the parts of the human body to remove heat therefrom by application of a relatively cold substance.

5 Prior to this invention it has been customary to effect such heat removal by applications of a cold liquid or solid, for example, cold water or crushed ice in a rubber bag. 10 These old methods are objectionable in that a cold liquid is insufficiently heat-absorbing because it can not pass through a point of fusion, as its temperature is raised, with consequent heat absorption equivalent to the 15 heat of fusion; crushed ice for filling a bag or ice cap can not be readily obtained within the home and unless it is finely crushed its uneven surfaces and edges cause bulges and projections in the surface of the bag to present 20 a uncomfortable and inefficient working surface; and when ice and water are used in the old type bags, continuous applications necessitate frequent refilling with attendant annoyance and wet outer bag surfaces.

25 It is the object of the present invention to overcome these disadvantages.

More specifically, this invention contemplates the provision of a cooling appliance which may permanently contain a substance 30 for effecting heat transfer; which may be used continuously, without emptying and refilling, by alternately removing the heat from the substance and applying it to the afflicted part of the body; and which will not burst 35 open or become distorted when water is frozen therein.

Further objects will become apparent from a study of the following description when taken in connection with the accompanying 40 drawings, in which

Fig. 1 is a plan view of the cooling device or container as inserted, ready for use, in a rubber envelope, the container being shown in dotted lines.

45 Fig. 2 is a horizontal section taken on line 2-2 of Fig. 1. Figs. 1-3 represent the preferred form.

Fig. 3 is a vertical half-section taken on line 3-3 of Fig. 1.

50 Fig. 4 shows a second form of container, it

being a modification of the left hand portion of the sectioned container of Fig. 2.

Fig. 5 discloses the modification of Fig. 4 with the filling opening in closed position and with a spring clip applied thereto.

55 Fig. 6 represents the projection of a portion of the surfaces and edges of the modified form of container upon a vertical plane, as would be seen when looking in the direction of the arrows on line 5-5, Fig. 4.

60 Referring to the drawings, 10 indicates a rubber envelope within which the container of the present invention may be inserted for use as a therapeutical device. This envelope is described and claimed per se in my co-pending application, Serial Number 264,804, filed March 26, 1928, and as its construction is readily apparent it is not thought to be necessary to describe it in detail here. It suffices to state that it is an envelope having end 70 tabs 11 which close the longitudinal passage therethrough by being buttoned at 12 to the main body; having slots 13 through which a holding strap may be passed; and having a plurality of spaced studs 14 upon one surface 75 thereof to prevent too rapid transfer of heat. Envelope 10 is only illustrative of a covering for the container as any type of rubber bag, cloth covering, and the like, might be used. In fact, the container might be applied separately from any enclosing member.

80 The container 15, made of metal, composition, or rubber, and in the form of a flask, may be shaped as desired and may be flat, or curved to fit the shape of the body to which it is to be applied. The space within the container is divided into a number of compartments by intersecting cross members or walls 85 16 and 17. The compartments are in communication with each other through a set of 90 apertures 18 in walls 16 and a set of apertures 19 in walls 17. The utility of this construction will later be explained.

95 The container may be filled with water, water and chemicals, or chemicals only. If water is used, the container should be only partially filled in order to prevent rupture thereof by the water when it freezes and expands into ice. For the same purpose, alcohol might be mixed with the water so that, 100

upon freezing, flaky crystals rather than a dense ice might be obtained. Water is preferably used because of the high latent heat of fusion of ice. When water is used, the problem of securing the necessary low temperatures presents itself. However, modern homes are today equipped with electrical or mechanical refrigerators of the type in which a freezing compartment is provided with 10 trays for making cubes of ice. One of these trays may be withdrawn and the container of this invention inserted in place thereof to quickly freeze the water or substance contained therein.

15 A liquid which expands upon freezing is liable to distort the container, due to the fact that under ordinary conditions the solidification starts at the surface and progresses downwardly. The walls 16 and 17 prevent 20 this condition by conducting the heat away with such rapidity that all portions of the liquid solidify at substantially the same time. In fact, the freezing starts at the bottom and sides of each compartment and works quickly 25 inwardly.

If a curved container (as in Fig. 2) should be partially filled with water and no interior compartments provided, the water would all 30 run to the ends of the container, freeze there, and burst the end walls. The plurality of compartments prevents this by segregating equal quantities of water in uniform distribution over the curved bottom surface. Before placing the container in the refrigerator, 35 it should be vigorously shaken in a horizontal plane, first in the direction of its transverse axis and then in the direction of its longitudinal axis, in order to cause the liquid to pass through apertures 18 and 19 for equal 40 distribution in the various compartments.

It is unnecessary to empty and refill the container for each application or period of use thereof. It may be filled by the manufacturer or by the user, and then permanently 45 sealed in any suitable manner, for example, by a plug 20 (Fig. 2).

As an example of a chemical that can be satisfactorily utilized in place of water or a mixture, benzene or benzole might be sealed 50 within the container. While the latent heat of fusion of benzole is not as high as that of water, a much greater quantity of the liquid can be safely used in the container. Because of its melting point, approximately 42° F., 55 it can be frozen by placing the container in close surface contact with ice or ice water. This is particularly advantageous in that it can be used in homes which have no electrical or mechanical refrigeration installed.

60 While the form shown in Fig. 2 may be made of metal, composition, or rubber, it is desirable, when employing a rubber container, to provide it with means for emptying and airing it out to prevent deterioration and 65 give it a longer life. The modification shown

in Figs. 4, 5, and 6 is illustrative of one form of such a rubber container. Except for the opening and closure means at one edge of the device, this modified construction is substantially identical with that shown in Fig. 2. 70 No covering is necessary and, due to the flexibility of the bag, it may be almost entirely filled with water. The walls 16 and 17 are preferably made of thick spongy rubber; thus when water freezes, most of its expansion will be taken up by compression of these rubber walls. As illustrative of a means for quickly opening and effectively closing the bag for filling, draining, and airing, a hole 21 (which may be much larger than that 75 shown in Fig. 5) is cut or formed at one edge. Several beads 22' are formed upon the inside of the container at one side of the hole and are adapted to nest, in closed position, between several beads 22'' on the opposite inner wall. Endless beads can not be used because when the rubber is folded along the line L a leak-proof seal will not be formed. For this reason the beads 22' and 22'' terminate approximately at the line L. A broad, 80 strong clip, substantially U-shaped in cross section, is slipped over the edge of the container to engage the outer surfaces thereof adjacent the beading and thereby to pinch and expand the rubber beads of each set into the corresponding depressions between the beads of the opposite set. An effective, 85 liquid-tight seal is thus formed.

I wish it to be understood that the drawings are merely illustrative of my invention and that various changes in the construction and combination of parts may be made within the limitations of the appended claims.

What I claim is:

1. A therapeutical device, comprising a comparatively thin container adapted to contain a liquid to be frozen and a plurality of intersecting walls in said container, said walls having apertures therein at points spaced from one side of the container, thereby forming a plurality of communicating compartments each adapted to hold separately a quantity of the liquid. 105

2. A therapeutical device, comprising a thin container slightly curved in cross section adapted to contain a liquid to be frozen, and a plurality of intersecting walls in said container, said walls having apertures therein at points spaced from the sides of the container, so as to form a plurality of communicating compartments each adapted to hold separately a quantity of the liquid and to prevent the concentration of the liquid in the lower parts of the container. 110 115

In testimony whereof, I have hereunto set 120 my signature. 125

EDGAR WOLTERS.
